NEGATIVE RESISTANCE CIRCUITS

Dietrich Prinz, Berlin, Germany, assignor to Tele-funken Gesellschaft für Drahtlose Telegraphie m. b. H., Berlin, Germany

Application June 28, 1933, Serial No. 678,036
In Germany July 22, 1932

4 Claims. (Cl. 179—171)

The present invention is concerned with the production and use of a drooping discharge characteristic in high vacuum tubes.

It has been known in the prior art that in high vacuum discharge tubes comprising a heated cathode, or filament, and additionally at least two electrodes, a drooping characteristic is obtainable if at least one of the cold electrodes exhibits adequate secondary electron emission.

10 The shape of such a characteristic as insured, e. g., by the inter-relationship between grid voltage and grid current in the presence of positive plate potential in a standard triode tube is represented in Fig. 1. The current initially rises to positive values seeing that in the presence of small grid voltages no secondary electrons are as yet generated, and it reaches negative ranges only where larger positive grid potentials are attained.

20 For a better understanding of the invention reference is made to the accompanying drawings, in which:

Figs. 1, 2, 4, 7 and 9 show characteristic curves of certain tube arrangements described,

25 Fig. 3 is a circuit diagram of a vacuum tube arrangement utilizing a negative resistance characteristic such as that of Fig. 2.

Fig. 5 is a circuit diagram of an oscillator arrangement made according to the invention,

30 Fig. 6 is an amplifier circuit diagram, and

Fig. 8 is an amplifier device connected and arranged according to the invention.

35 The object of the invention resides in the production of a characteristic in which the current from the very outset assumes negative values, as shown in Fig. 2, instead of assuming initially positive values as shown in Fig. 1. According to the present invention, with the said end in view, recourse is had to a tube equipped with two grids, say, a screen grid type of tube. The key diagram used therefor is shown in Fig. 3. The inner grid (control grid) is given such a high negative biasing voltage that a current will be able to flow to the outermost grid (screen grid) and towards the plate only in the presence of such high screen grid potentials that the coefficient of secondary electron emission of the screen grid becomes essentially greater than unity (1); in other words, that the number of electrons issuing from the screen grid is greater than the number of electrons impinging thereon.

40 The result is that the screen grid current will have a negative value from its very incipiency so that the graph giving the relationship between screen grid voltage and screen grid current will have a shape as illustrated in Fig. 2. Supposing that the coefficient of secondary emission is essentially constant, then the resultant negative screen grid current will be proportional to the 45 originally primary screen grid current, and will

have the form of a normal space charge curve $i=K.V^{3/2}$ comprising a negative factor of proportionality K.

Now, according to the present invention, this fact is used for the object of producing characteristics of extremely high positive or negative slope. What is used to that end is a standard triode tube whose mechanical dimensions and whose grid biasing voltage are so chosen that its characteristic is just the reflected image of the drooping characteristic shown in Fig. 2; in fact, a characteristic of this kind is represented on the right-hand side in Fig. 4. On the other hand, by simple reversal of polarity of an arrangement shown in Fig. 3, what is obtained from the characteristic Fig. 2 is a characteristic which is shown on the left-hand side in Fig. 4. In other words the device of Fig. 3 gives the characteristic curve of Fig. 2 when the positive direction for current is taken as into the screen grid from the cathode and positive direction of voltage is cathode negative, screen grid positive. If now the polarity of the basic plus directions for voltage and current are reversed we get the characteristic shown at the left side of Fig. 4.

By connecting in series the said two arrangements what is then obtained is a characteristic which is due to that the voltage values corresponding to a definite value of the current, and shown by the curves in the left hand and the right hand side in Fig. 4, are added to one another. However, owing to the symmetry of these curves what results is a straight line which coincides with the current axis, and which, in other words, possesses an infinitely great slope, theoretically speaking. But, by providing slight departures in the shape of the two characteristics conditions in practice can be made so that this slope will assume very high and finite positive or negative values.

45 Fig. 5 shows the use of such an arrangement for the purpose of wave generation. Referring to the same, 1 denotes the screen grid tube which furnishes a characteristic as in Fig. 2 or the curve on the left hand side Fig. 4; 2 denotes the plain, or single grid, tube whose characteristic is shown on the right hand side, Fig. 4. 3 and 4 are the inductance and capacity comprised in an oscillation circuit which determines the frequency of the oscillations generated. Now, it is well known that the production of oscillations by the aid of drooping characteristics of the dynatron type is predicated upon that the absolute value of the negative resistance of the drooping characteristic must be smaller than the impedance of the oscillation circuit. A low absolute value of negative resistance, however, is equivalent to great steepness of the characteristic. In other words, the greater the slope, the more readily will waves be generable also in circuits involving marked damping, i. e., low impedance.

Now, basically speaking, it is feasible to insure very great slope values by that any desired drooping characteristic of the dynatron type is arranged in series with a resistance the size of which corresponds to the maximum slope of this characteristic. However, owing to the curvature of the characteristic, the new characteristic which results because of the addition of the resistance will have an infinitely great slope only in the immediate neighborhood of the point where the original characteristic had its maximum slope. The result is that waves thus generated will be able to assume only very small amplitudes. However, in an arrangement as here disclosed, by the combination of a rising and a drooping characteristic of practically identical forms, an extremely great slope is attained inside a wide range of potential as has been explained above in more detail. The result is that with such an arrangement oscillations of considerably larger amplitude are generable. In the oscillator arrangement of Fig. 5, the rising characteristic of the triode 2 is balanced as it were by the drooping characteristic of the screen circuit of tube 1 so that a resultant very steep characteristic, such as that shown by the part of the current axis which is made heavy in Fig. 4, is obtained. Under these conditions a very small change in grid voltage of tube 2 will produce a large change in its plate current, causing the tuned circuit 3, 4 to oscillate at its natural frequency. After oscillations are once initiated they will be maintained by the negative resistance of the screen grid circuit.

Another application resides in the amplification of alternating potentials in a circuit scheme known as resistance-coupled amplifiers. The principle underlying is indicated in Fig. 6; R_a denotes the external resistance, E_a the plate battery. The operation of such a circuit scheme is representable as well known in the following manner:

For two different grid voltages, say, -10 and -11 V, one plots the graphs giving the interrelationship between the plate current I_a and the plate voltage V_a (Fig. 7). In this diagram is plotted, furthermore, the characteristic of the system which consists of the plate battery E_a and the external resistance R_a .

This characteristic is a straight line intersecting the V_a -axis at the point where $V_a = E_a$, and which presents an inclination being the reverse of the inclination of the characteristic of resistance R_a itself; in other words, which exhibits a tendency towards increasing currents with decreasing potential. The points of intersection between this straight line and the tube characteristics then result in currents I_{a1} and I_{a2} and voltages V_{a1} and V_{a2} which flow through or are active across the tube in the presence of grid potentials -10 and -11 V. The difference $V_{a2} - V_{a1}$ in other words, results in the plate potential difference per 1 V grid potential difference, i. e., directly in the voltage amplification that has been obtained.

According to the invention, however, instead of the resistance R_a a system as shown in Fig. 3 is used which presents a characteristic of the kind shown in Fig. 2, the dimensions in this scheme moreover being chosen in such a manner that the form of the characteristic agrees almost exactly with the characteristics Fig. 7.

The operation of the arrangements shown in Fig. 8 flows from Fig. 9. Instead of a straight line, Fig. 7, there is obtained here a curve which is obtained from the curve Fig. 2 by tilting the same over, and the applied plate potential E_a may become here of zero value, if dimensions are chosen appropriately. As can be readily seen the whole or resultant characteristic of the amplifier arrangement of Fig. 8 is covered by a change of 1 V in the grid potential so that the differences $V_{a2} - V_{a1}$ and $I_{a2} - I_{a1}$ are substantially greater than the use of an ordinary resistance. The resultant characteristic is shown by the middle curve of Fig. 9 from which it is evident that a small change of the control grid voltage V_g of the triode of Fig. 8 results in a large change in the plate voltage thereof. This arrangement therefore forms a very efficient voltage amplifier of any signal voltages applied to the triode grid, and the amplified voltage variations may be utilized by connecting to the triode plate circuit. In other words, the tube arrangement shown is Fig. 8 affords a far higher gain. What should also be mentioned is that the arrangement as here disclosed offers this advantage over other arrangements known from the prior art in which the plate circuit of the amplifier contains another discharge tube acting as an external resistance, that the said second tube is not connected the reverse of the first, but that its filament is united with the filament of the first tube so that harmful effects due to ground capacitance of the sources of the filament are unable to arise.

What is claimed is:

1. An amplifier arrangement comprising the combination of a triode having a cathode, a control grid and plate, a second tube having a cathode, a first grid, a plate and a screen grid located between said first grid and plate, a circuit coupling said triode plate to said screen grid, and means connected to impress a high negative biasing voltage on said first grid.
2. The combination defined in the preceding claim in which a conductive connection is provided to connect the cathodes of the tubes.
3. An amplifier arrangement comprising the combination of a triode having a cathode, a control grid and a plate, a second tube having a first grid, a screen grid and a plate, means for applying a high positive potential to the last named plate, means for applying a high negative biasing voltage to said first grid whereby said screen grid emits secondary electrons and a lead conductively connecting said screen grid and said triode plate.
4. A circuit arrangement comprising a vacuum tube having a cathode, a control grid, a plate, and a screen grid positioned between the control grid and plate, means for applying a high positive potential to said plate, means for applying a lesser positive potential to said screen grid than that applied to said plate, and means for applying such a high negative biasing voltage to said control grid that there is no flow of electrons from the cathode into the screen grid and also the flow of secondary electrons from the screen grid increases as its voltage is increased.
